Specification of Letters Patent. Patented Aug. 11, 1914.

Application filed November 21, 1905. Serial No. 288,369.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object the provision of means for handling the load on the exchange switchboards with greater uniformity and efficiency than has heretofore 15 been possible.

I attain my object by employing what I may designate as an auxiliary switchboard, which during the busy hour takes care of the overflow from any or all of the main switch- 20 board positions, and during the quiet hours takes care of the entire load, the main switch- board being then put entirely out of service.

It is the object of my present invention particularly to care for the variation in load 25 between operators during the busy hour, by permitting certain conditions to throw anything above a maximum normal load on to an auxiliary switchboard. This may be done by the operators themselves, or it may be 30 done automatically. The latter method will not be specifically claimed herein, the specific claims in the present case being limited to the manual overflow control. I provide means whereby after the load has fallen to 35 a certain point, connections may be made at all the main board positions to throw the entire load on the auxiliary board. This board would ordinarily only have a few positions, hence patrolling becomes unnecessary.

My invention is illustrated in the accompanying drawings, wherein—

Figure 1 is a diagram showing two subscribers' stations with terminal jacks and signals and an operator's cord-circuit on the main switchboard in a central office; also a primary selector and a special trunk circuit for throwing calls from the main board to an auxiliary board. Fig. 2 is a similar diagram, 50 complementary to Fig. 1, showing the circuits of the auxiliary board. Fig. 3 is a view of a modified switch circuit.

I have heretofore spoken of that portion of the equipment which carried the overflow 55 and the night load, as an "auxiliary" board.

Before proceeding with the detailed description I wish to state plainly that while this special section may truly be called an auxiliary switchboard where it is added to an existing exchange, it can and should quite as 60 truly be called an equalizing section, where it is furnished as part of the original equipment. If the main switchboard is a multiple board, this equalizing section may also be equipped uniformly with the rest of the 65 board, although I shall hereinafter describe it as equipped with semi-automatic circuits for connecting lines. The real function of this special section is to provide one definite part of the switchboard equipment which 70 will be complete in itself, and will concentrate upon itself the constant wear, which as I have pointed out would otherwise be unequally distributed over the various regular sections of the switchboard. 75

Referring now to Fig. 1, A is a subscriber's station equipped with the usual transmitter, receiver, switch-hook, ringer and condenser. From this substation the line-wires 1 and 2 pass to the contacts *n* and *n'* of the cut-off relay *N*, which normally rest against back contacts, connecting the line to the lamp relay *M*, and the main battery *B*. When the relay *N* is energized it cuts off the line-relay *M* and connects the 80 line through its front contacts to the jacks *J*, and also to multiple contacts in one or more primary selector switches *P*², to which reference will be made in a moment. 85

A' is another subscriber's station similar 90 in all respects to the station *A*, and similarly equipped. Its branches to the primary selector switches are not shown in full, being indicated only by the stub lines 7 and 8. 95 The corresponding wires for station *A* are marked 5 and 6. For interconnecting the lines through the jacks, *J*, *J'*, on the main switchboard sections, I provide the usual cord-circuits comprising a pair of plugs, *P*, *P'*, connected by cord-conductors 9, 10, 11, 12, and equipped with supervisory lamps, *s*, *s'*, controlled by the relays *S*, *S*² and *S'*, *S*³, which are bridged on the main battery *B*. 100

So far, the equipment is of a usual and well-known type, with the addition of the primary selector. The operators on the main switchboard sections use this equipment in the regular way up to the point where they become overloaded, that is, where they are forced to leave calls un- 105 110

answered because of their number and concentration. When this condition is reached recourse is had to special trunking plugs P^3 , each forming the terminal of a trunk line 13, 14 leading to a spring-jack J^2 on the equalizing or auxiliary switchboard section. It will be observed that the ordinary answering and calling plugs P , P' ; each have a tip and sleeve contact only. The overflow plug P^3 , however, has tip, ring and sleeve contacts, for a purpose which will appear in connection with the primary selector operation. The tip of the plug is so made that it may pass in the jacks, J or J' beyond the spring contact, the line-circuit being carried by the ring and sleeve p' , p^2 . The incoming trunk jack J^2 on the auxiliary section has three contacts, two springs and a sleeve, the answering plugs on this auxiliary board being therefore three-contact plugs; for convenience in making the cut-off and other controlling connections.

When an operator becomes loaded, and a call comes in which she cannot handle, she inserts the plug P^3 in the calling line-jack J , continuing the line-circuit as I have said through 15—16, 13—14 to the springs of the jack J^2 on the auxiliary board. The relay S^6 and the relay S^4 then act in the same manner as the relays S^2 and S of the ordinary cord-circuit. That is to say, current flows from the main battery through the back contact of relay S^6 by way of wires 17, 18, 19, 20, through the sleeve relay S^5 , trunk wire 14, and jack wire 16 to the cut-off relay and ground. When this cut-off relay pulls up the flow of current continues through the line and back to the ring contact p' , the tip side 13 of the trunk, and through relay S^4 to ground, by way of wire 21 and another back contact of the cut-off relay S^6 . Relay S^5 pulls up in series with the line cut-off relay N , and puts battery on the wire 22, the relay S^4 disconnecting wire 22 from the supervisory lamp s^2 , as long as the subscriber has his phone off the hook. The cut-off relay S^6 is grounded on one side and is connected on the other side by wire 23 to the sleeve contact of the trunk jack J^2 on the auxiliary board. Associated with this trunk-jack is a signal lamp m^2 , grounded on one side and connected on the other through a wire 24 with the wire 22 on the main board, so that when the plug P^3 is inserted 55 in a calling line-jack, and the relay S^5 pulls up in consequence, battery will be put on the wires 22 and 24 to light the lamp m^2 on the auxiliary board, indicating a call to be answered there. When the answering plug on 60 the auxiliary board is inserted in the jack J^2 , battery is thereby put onto the wire 23, whereby the cut-off relay S^6 is pulled up, and the wires 19 and 21 disconnecting from the battery and ground, respectively, breaking 65 the bridge across the trunk, deenergiz-

ing the relays S^4 and S^5 , and leaving the talking wires from the line to the jack J^2 absolutely clean and clear. This cut-off relay S^6 remains energized as long as the plug is in the trunk-jack on the auxiliary board, 70 and at the same time battery is fed back from the cord-circuit on that board through the trunk-conductor 14 and the line extension 16 to the cut-off relay N to hold it up.

It may well be stated in this connection 75 that while I have shown the line-circuits herein of a standard and well recognized "two-wire multiple" type, I do not by any means limit myself to such line-circuits, nor to any special cord-circuits. Line and cut-off relays, with supervisory relays in the cord-circuits, are found in all common battery systems, and such changes as the addition of contacts in the jacks or of third conductors in the cords, are clearly incidental, 85 so that the circuits I present herein can be changed by any engineer or skilled factory draftsman to suit any particular system to which they are to be applied.

Before passing from Fig. 1 I will briefly 90 describe the primary selector switch P^2 and its connections. This switch is intended to take the place of an answering plug, under certain conditions, to connect any one of a considerable number of lines which may be 95 calling, to the jack J^3 and so to the trunk 13—14 onto the auxiliary board. The jack J^3 may and will be resorted to by the main board operator, when automatic overflow is desired. Suppose the load has reached the 100 overflow point, the operator can insert the plug P^3 in the jack J^3 , and thereby the wires 14, 13 and 25, terminating in the sleeve, ring and tip of the plug, respectively, become extended through the wires 26, 27 and 28 to 105 the contacts p^{10} , p^{14} , p^{15} of the switch P^2 . This switch has a circular series of contacts, arranged around a central spindle p^4 , which may be constantly rotating, or it may be started to rotate when connection is made 110 with the switch.

The spindle is of steel or iron and forms the core for an electromagnet p^3 , which has an iron head p^{30} and an iron tubular shell secured to the head, and carrying an armature p^5 at its lower end which is centrally perforated to permit the passage of the spindle p^4 . On the spindle is rigidly secured a disk p^6 having a notch in its upper surface adapted to receive a pin or stud p^{60} on the 115 armature p^5 . The armature carries a lever p^7 , whose upper end extends into a slot in a tube p^{31} fixed radially upon the head of the magnet. This tube contains a plug p^{16} of insulating material, which is adapted to be 120 slid back and forth in the tube by the armature lever p^7 , whose upper end is received in an opening in the plug, and plays back and forth in the slot in the tube. Mounted upon the lower end of the lever p^7 are the two in- 125

suluted contact springs p^8 and p^9 , which serve not only to establish the circuits through the magnet p^3 , but as retraction springs to keep the lever and plug in the normal position shown in the figure. These two springs bear upon the fixed contacts p^{10} and p^{11} , respectively. The former, p^{10} is a continuous ring, and the latter p^{11} is associated with the set of line-contacts in the case of each line, each one of the contacts p^{11} serving when its potential is raised by the energization of magnet M to permit the magnet p^3 to become energized when it is reached by the spring p^9 , to stick the plug p^{14} into what may be called the individual line-jack, to connect the line-terminals p^{12} and p^{13} to the jack and trunk terminals p^{14} and p^{15} . The magnet p^3 has two windings, which may be end-on windings, or one outside of the other like the windings of an induction coil, or preferably put on in layers, first a layer of No. 1, then a layer of No. 2, the layers separated by paper, and the inner ends of both windings grounded on the tubular core. The core upon which the magnet is wound, is necessarily hollow or tubular, to permit the passage of the spindle p^4 , and the magnet except when locked to the spindle by the pin p^{60} on its armature, is free to turn thereon, being supported by one or more studs p^{40} , which take into an annular groove in the spindle and turn therein.

The spring p^8 is connected to one winding and the spring p^9 to the other winding of the magnet p^3 . When a line is calling it is the spring p^9 which picks up current from the line-contact p^{11} at that point in the rotation of the spindle, this current passing through one magnet winding of p^3 and to ground through the spindle, energizing the magnet, pulling up the armature p^5 , and sticking the plug p^{14} between the springs p^{14} and p^{15} , whereby the wires 5 and 6 are connected through 26 and 27 to the jack J^3 , plug P^3 , and trunk-wires 14—13. Current over 14 from the main battery at once energizes the cut-off relay N of the line, the result being the same as if a manual plug P had been inserted. In order to hold up the magnet p^3 I provide the second winding and the ring contact p^{10} for each switch. After the switch has once stopped to connect a particular line, the trunk-wire 25 is connected through wire 28 and contact p^{10} to the spring p^8 and the second winding of the magnet. This trunk-wire 25 is normally open at the contacts of relays S^4 and S^5 , either of which however can put it on battery, the first by way of wire 22, when the primary selector P^2 stops, this serving to hold the magnet p^3 until the auxiliary operator plugs in on the jack J^2 ; the other relay S^6 puts battery on the wire 25 direct, at the same that it cuts off the two relays S^4 , S^5 , the relay S^6 itself becoming energized only

when the auxiliary operator plugs in at J^2 . The circuits for these successive steps will be traced in the statement of operation herein-after, but it will now be seen that the primary selector P^2 , finding a line calling in its rotation, stops with the spring p^9 on the contact p^{11} of that line, and shorts in the plug p^{14} ; thereupon an effect is produced the same as if a manual plug had been inserted, the relays S^3 and N become active, followed by the relay S^4 , the switch then being held by current through wires 22 and 25. When the auxiliary operator comes in at J^2 , magnet S^6 is energized and the further control of the switch is given to the auxiliary operator, through the wire 23 and the said relay S^6 .

Referring now to the diagram in Fig. 2, the arrangement of the switch F will be understood from the foregoing statement, read in connection with the following: The magnets f^8 , f^9 and f^{11} are controlled by the relays f^{80} and f^{110} . The side switch magnet f^{17} is controlled by the rotary relay f^{170} . Magnets f^{18} and f^{19} are merely bridging magnets or choke coils, across the calling end of the switch trunk, included in the connection 30, 31, of the main battery B , through which talking current is supplied to the called subscriber. The vertical and rotary relays f^{80} and f^{170} are permanently bridged on the answering end of the switch trunk, which is separated from the calling end of the condensers C' . g is the ringing relay, connected to the last contact point of the side switch-arm f^{12} on one side, and to the battery wire 32 on the other. f^{11} , as already stated, is the release magnet, controlled by the relay f^{110} , which in turn has its circuit closed in either one of two ways, first by both the relays f^{80} and f^{170} being energized at once, second by being connected to the second point of the side switch-arm f^{15} by the relay f^{17} and in response to the last rotary impulse for testing the line wanted after it has been selected.

P^4 and P^5 are the answering and calling plugs, respectively, of a pair on the auxiliary board, connected by the conductors 33, 34, 35 and 36, which include the condensers C . The plug P^4 has three contacts, a tip, ring and sleeve, marked p , p' , p^2 . The tip and ring are connected to the wires 33 and 35, while the sleeve is connected through wire 37 to a cut-off or release relay F' , the armature of which is shown as grounded, and normally resting against the terminal of the wires 38 and 39, which are tapped onto the cord-conductors 34 and 36.

Associated with the calling-plug P^5 is a sender, or number transmitter, which I have indicated diagrammatically at O , with a spindle o carrying teeth o' and o^3 co-operating with springs o^2 , these springs being connected through wires 40 and 41 with the two

cord-conductors 34 and 36, and the spindle being grounded through the wire 42. In operating this form of sender the button o^4 is pressed down, and a pin o^6 passing into a slot o^6 in the tubular upper end of the spindle o , turns the latter so that the teeth o' do not touch the springs o^2 in going down. In coming back, however, the inner spindle carrying the button o^4 is pressed up by a suitable retracting spring not shown, and its first movement upward turns the sleeve back so that the teeth o' and o^3 turn into contact with the springs o^2 . I do not of course limit myself to the use of this special sender, as any suitable type may be employed. The idea is that by pressing down the button a greater or less distance any number of impulses up to ten may be sent by the teeth o' contacting with the spring 40, and always at the end of every set of such impulses a single impulse will be sent by the one tooth o^3 .

In the cord-circuit of Fig. 2, the relays S^7 and S^8 correspond precisely to the relays S^1 and S^2 in Fig. 1. They jointly control the supervisory lamp s^3 , and this lamp indicates to the auxiliary operator when the calling subscriber has hung up, the control of the connection being given to him. When the plug P^4 is thereupon pulled out from the jack J^2 , the relay F' lets go and grounds both cord-conductors 34 and 36, thereby energizing both relays f^{10} and f^{11} of the automatic switch F , which energizes the release relay f^{10} and the release magnet f^{11} , to restore the switch.

Two points should be distinctly understood here. One is that the employment of the automatic switch F is optional, although I shall claim it. The jack J^4 on the auxiliary board, whose trunk wires 43 and 44 pass to the automatic switch F , may be replaced by the multiple jack of a subscriber's line. In other words, the automatic switches F contain the multiples f^3 of subscriber's lines, which may well be replaced by ordinary multiple jacks on the auxiliary board, in such case the senuer O being done away with, and each auxiliary operator upon receiving a call trunked from the main switchboard would merely test, plug in and ring in the ordinary way. Such claims as I shall make hereinafter covering the combination of the main and auxiliary boards and their working broadly, are intended to include the foregoing or any other arrangement by which the auxiliary operators may have access to the subscribers' lines for calling purposes. I prefer automatic switches however, as shown.

The second point to be understood is this, that while I have shown the control of a semi-automatic connection as being entirely in the hands of the calling subscriber, the auxiliary operators having only what may

be called "single" supervision, nevertheless control can be given to both of a pair of connected subscribers, so that neither can be "hung" up and prevented by the other from getting further connections. In order that the called subscriber will release himself, I provide the magnets f^{18} and f^{19} , in Fig. 2, with back release contacts, which in series with the contacts of a separate self-locking relay, control the release magnet f^{11} . The self-locking relay pulls up through front contacts of the two relays f^{18} and f^{19} , or either one of them, or in other words when the called subscriber answers. Being up and locked, this self-locking relay connects the circuit of the magnet f^{11} to the back contacts of one or both of the relays f^{18} , f^{19} , so that when they release their armatures upon the called subscriber hanging up, the release magnet will be energized and the switch restored to zero. In such case I provide a pair of contact springs in the locking circuit of the self-locking relay, to be opened by the switch spindle f in its normal or idle position. This arrangement is illustrated in Fig. 3 of the drawings.

The operation of my improved system will be understood from the foregoing description, but may be briefly stated as follows: Assuming that subscriber A desires connection with subscriber A', he removes his receiver from the hook, the lamp m lights, the operator inserts with P , and completes his connection with J' , as usual. Assuming, however, that the operator is already attending to several connections, or has all her cord-circuits busy, upon perceiving the lighting of the lamp m , she inserts the plug P^3 in the calling line jack, and pays no further attention to it. The insertion of the plug P^3 closes its ring and sleeve p^1 , p^2 on the spring and sleeve of the jack J , and the cut-off relay N takes current over the following circuit: B, 18, 19, S^5 , 20, 14, p^2 , 16, N , ground. The relay M is thereby cut off, and the line-wires 1-2 put onto the extensions 15-16 and so onto the trunk-wires 13-14. The relay S^5 pulls up in series with the cut-off relay N , and the relay S^4 now follows. The lamp s^2 thereby remains extinguished, but it will be observed that when the relay S^5 became energized that a circuit was at once completed for the lamp m^2 on the auxiliary switchboard as follows: B, 18, 19, 22, 24, m^2 and ground. Thereupon the lamp m^2 lights, and the auxiliary operator inserts the plug P^4 in jack J^2 . The insertion of the plug connects its cord-conductors 33 and 35 to the trunk-wires 13-14, and completes the following cut-off circuit for the relays S^6 in the trunk and F' in the cord. B (Fig. 2), F' , 27, p^2 , sleeve of J^2 , 23, S^6 and ground. Both these relays then pull up, the relay S^6 cutting off the wires 19 and 21 and thereby

removing the relays S^4 , S^5 from the trunk-circuit, and also breaking the battery connection through wire 19 to wire 22, whereby the lamp m^2 is put out, and the lamp s^2 cannot light until the plug P^4 is withdrawn. The removal of battery from the wire 19 would deenergize the cut-off relay N of the calling line, except for this fact, that simultaneously with the cutting off of wire 19, battery is put on through the relay S^8 in Fig. 2 and back through the cord-conductor 35 and the trunk-wire 14 to keep the relay N energized. It will be observed that the trunk circuit after the plug P^4 is inserted is perfectly clean and clear, so that the line is really put right on the auxiliary switchboard. Having ascertained the number wanted, the auxiliary operator takes up the plug P^6 and inserts it in a jack J^4 of a hundreds group containing the line wanted. Each connector switch F containing the terminals of one hundred lines, it follows that the trunks from these switches can be grouped by hundreds, and the operator can therefore make one selection by simply plugging into the proper group. Having done so she sends the tens and units number by manipulating the sender O . Suppose the number of the subscriber wanted was 4468. She plugs into jack J^4 of group 44, and presses down the button o^4 to the sixth tooth, which may be indicated by numbers on the stem or in any other suitable way. The button returning completes the following circuit six times: B, 32, f^{80} , 43, J^4 , P^5 , 34, 40, o^4 , o^4 , 42 and ground. The relay f^{80} is therefore energized six times, and closes the following circuit six times: B, 32, f^9 , f^{12} , 45, 46, 47, 48 and ground. Magnet f^9 thereupon steps up the wipers f^2 to the 6th row of line-contacts. As the button o^4 gets to its uppermost position the following circuit is completed, viz. B, 32, f^{170} , 44, J^4 , P^5 , 36, o^2 , o^3 , 42 and ground. Relay f^{170} thereupon closes the circuit of magnet f^{17} once as follows: B, 32, 49, 50, 48 and ground. This opens the wires 45 and 46 and makes a back and forth movement of the escapement which moves the side switch-arms along one step, whereby magnet f^9 is cut off and magnet f^8 is connected to wire 45. The operator then presses down key o^4 to the eighth tooth, and upon its rising eight vertical impulses over the wires 34 and 43 are followed by a single impulse as before over the wires 36 and 44. The eight vibrations of relay f^{80} cause the magnet f^8 to step around the wipers f^2 to the eighth contact in the sixth row, which is number 68. A single impulse over 36—44 causes relay f^{170} to energize f^{17} , which pulls up and closes together the test wires 51 and 52, at the contacts 53. The idle switch-arm f^{15} is still on the second contact, and during this upward motion of the armature of magnet f^{17} the arm remains on this contact, so

that the following circuit is completed to test: B, 32, f^{110} , 51, 53, 52, f^{15} , and to the tip side of wiper f^2 . Now this wiper is resting on the tip contact of the line wanted. If that line is already busy, there is either a plug in its jack, or some other switch wiper on its tip contact. In the first case there is a ground on the tip side of the line through the relay S of Fig. 1; and in the second place there is a ground on through the tip wiper f^2 and the magnet, f^{18} , of such a switch as is shown in Fig. 2. In either case, the relay f^{110} of the switch with which we are testing, pulls up, closing the circuit of the release magnet, which is obvious, so that this magnet instantly releases the switch, which turns back to the beginning of the row and drops its spindle to normal position. It should be observed that this release of the switch is effected before the arms of the side switch have gone to the third point, and therefore before any connection has been effected with the line wanted.

It is my intention to have the ringing of the called subscriber made automatic. Assuming that the line wanted is not busy, then there will be no ground on its tip side, and the relay f^{110} will not pull up, so that the relay f^{17} will let go with the switch remaining in position. Upon its letting go, the side switch-arms are all made to take the third step, whereby both magnets f^8 and f^9 are cut off, and the wire 45 is connected to the wire 54 running to the ringing relay g ; the trunk-wires 55 and 56 are connected to their extensions 57 and 58, through the contacts of the ringing relay, and the arm f^{15} passes on to its last contact. The ringing relay g is thus put into control of the vertical relay f^{80} , and the ringing may be accomplished in any one of several ways. First, the operator may punch the same button o^4 to any indeterminate point, and the consequent impulses will energize the ringing relay g a corresponding number of times to put the generator G on the wipers f^2 . Second, the operator may have a button to ground the wire 34 and hold it grounded for the same purpose, or she may press down the button o^4 and hold one tooth in contact with the spring o^2 as the button rises. Other means for controlling the ringing relay or the ringing current, and other methods of starting the same in operation may be employed. These methods of ringing are not essential features of the present invention, although I shall claim automatic ringing, because I plan to save the auxiliary operators the labor of ringing and supervising after completing the connection.

After the subscribers have finished their conversation, and have hung up, the calling subscriber having control of the connection, his circuit is broken at the switch-hook of station A, and the relay S^7 in Fig. 2 lets

go its armature. This closes a circuit from the battery B to the lamp s^3 , which lights, apprising the auxiliary operator that disconnection is desired. She thereupon pulls 5 first the plug P^4 , whereupon the relays S^4 and F' , in Figs. 1 and 2, become deenergized. The former restores current to the lamp s^2 and the relay S^5 , this lamp apprising the main board operator of the desire 10 for disconnection. The relay F' letting go, grounds the wires 34-38 and 36-39, so that both relays f^{50} and f^{170} pull up simultaneously, closing the release circuit through relay f^{110} . The switch F is thus restored, and 15 as this effect is produced the instant the plug P^4 is pulled, the operator can proceed at once to pull plug P^5 on the auxiliary board. The lamp s^2 notifying the main board operator, she withdraws the plug P^3 , 20 and everything is restored to normal.

It will be noticed that after the auxiliary operator has withdrawn P^4 from the jack J^2 , that the circuit of lamp m^2 is again completed until the main board operator has 25 pulled the plug P^5 . To avoid any danger of false signals, I may provide a separate cut-off relay for this lamp, energized in parallel with the relay S^6 , through the wire 23, and locking itself on the wire 22, this relay 30 being made more sluggish than the relay S^6 , so that when the plug P^5 is pulled, the locking circuit will be reestablished from the battery B through wire 22, before the relay has time to let go. Then when the plug P^5 35 is finally pulled, and battery is taken off the wire 22, this relay will have its locking circuit broken, and so let go, again completing the circuit of lamp m^2 through the wire 24 ready for another advanced signal.

40 The foregoing action depends upon the main board operator sticking the plug P^5 . I may, however, through the primary selector P^2 do the same thing automatically. When the load curve has risen to a predetermined point, the main board operators may 45 insert their plugs P^5 in the jacks J^3 and leave them there. The spindle p^4 of each primary selector is supposed then to be turning, controlled in common by the lines 50 in its group, through their line relays M or in any other satisfactory manner. Suppose line A calls. The lamp m will light, and at the same time the contacts p^{11} of the line in all of the primary selector switches will 55 have their potential raised. The operator being busy, the first primary selector that reaches a line contact p^{11} gets a completed circuit as follows: B, 17, 60, 61, p^{11} , p^9 , winding of p^3 and ground. This energizes 60 the core, spindle and shell of p^3 , and causes the armature p^5 to be pulled up, pulling the stud p^{60} out of its socket in the collar p^6 , throwing forward the lever p^7 pushing the plug p^{16} into the individual line-jack 65 through the opening p^{160} in the jack ring,

and spreading the springs p^{14} , p^{15} into contact with the springs p^{12} , p^{13} , thus connecting the wires 26 and 27 with the line extensions 5-6. Since the wire 26 is already connected through the jack and plug J^3 , P^5 , respectively, to the wire 14, the effect of the insertion of plug p^{16} is to connect the trunk 13-14 to the line just the same as though the plug P^5 had been put in the jack J . In other words, current flows from the battery 75 B, through the relay S^5 to the sleeve side 6 and so to the cut-off relay N, which puts the line-wires 1-2 on the extensions 5-6, and cuts off current from the relay M which in turn cuts off current from the lamp m 80 and the wire 61. The line contacts p^{11} therefore become dead again the instant any arm picks up the line, so that no other of the primary selectors will get on the same line.

85 The instant the line is put on the wires 5-6 current flows back through wires 1, 5 and 27 to the trunk wire 13 and relay S^1 , which puts battery current from the wire 22 onto the wire 25, and so by way of the tip p 90 and the wire 28 to the ring contact p^{10} of the primary selector in use, continuing a locking circuit therefor through the springs p^8 , the second winding of magnet p^2 , and ground. When the plug P^4 of the auxiliary operator 95 is inserted in the jack J^2 , current is maintained on the wire 25 for this same purpose through the wire 18 controlled by the relay S^6 , and it will be observed that the further operation on the part of the auxiliary operator, and the control by the calling subscriber, are the same step-by-step as those which I have described before. When the plug p^{16} of the primary selector switch goes 100 into a calling line-jack, it puts the line 105 through on the trunk and the flow of current through relay S^5 lights the lamp m^2 by putting battery on the wire 24. It is thought that the subsequent steps need not be recapitulated, as they will be sufficiently understood from the previous statement of 110 operation.

Having thus described my invention, what I claim and desire to secure by Letters Patent is:

115 1. In a telephone exchange system, subscribers' lines, a main switchboard having subscribers' calling and answering terminals, an auxiliary switchboard having trunk terminals and subscribers' calling terminals 120 only, connective trunks between said main switchboard and said auxiliary switchboard, automatic means at the main switchboard for trunking calls to the auxiliary switchboard and means at the latter board for answering the calls and making the connections desired.

125 2. In a telephone exchange system a main switchboard and an auxiliary switchboard, means for receiving and answering calls and 130

making connections on the main switchboard, a trunk line having automatic switching means controlled at the main switchboard and adapted when active to pick up 5 the calling subscribers' lines, said trunk line also having a connection terminal on the auxiliary board, whereby any call thus picked up may be answered, and means on the auxiliary board for completing the connections desired.

3. In a telephone exchange system a main switchboard and an auxiliary board, answering and connecting apparatus at the main switchboard for all the lines, trunk 15 lines between the main board and the auxiliary board, each trunk line having a primary selector switch containing subscribers' line terminals in multiple with those on the main board, and each trunk also having an 20 answering terminal on the auxiliary board, whereby calls may be answered and connections completed thereat.

4. In a telephone exchange system a plurality of subscribers' lines, a main switchboard equipped with a manual connecting apparatus, and auxiliary automatic connecting means adapted to be set upon the occurrence of an overload on the main switchboard, to respond to calls over the subscribers' lines, and thereupon to select and effect 30 initial connection of said lines apart from the main switchboard.

5. In a telephone exchange system, a main switchboard having manual answering and connecting terminals, an auxiliary switchboard having automatically actuated switching means for answering calls over the same subscribers' lines, connecting means associated therewith, operators' controlling means therefor, and automatic releasing means for the connecting means.

6. In a telephone exchange system, a main switchboard containing the terminals of subscribers' lines and provided with manual 45 means for answering calls and completing connections over the same, an auxiliary switchboard, automatic selector switches containing line terminals for trunking calls from said lines to the auxiliary board, and 50 means controlled at the main board for rendering said switches active.

7. In a telephone exchange system, a main switchboard equipped with manual answering devices and connective apparatus and an auxiliary switchboard having automatic 55 line seeking switches containing line multiples for answering and switching overflow calls from the manual board.

8. In a telephone exchange system subscribers' answering terminals and operators' 60 connective circuits adapted to connect the subscribers' lines with automatic connector switches, an operator's sender associated with the connective circuits to operate the switches, and means actuated in effecting 65 disconnection from the calling line to release the connecting switch in any case and so clear the called line.

9. In a telephone exchange system calling line-terminals as J^2 , operators' answering 70 plugs as P^4 , connections from said plugs to automatic switches as F , an operator's sender O , and means as F' associated with each answering plug P^4 for releasing and restoring the automatic switching apparatus upon 75 the plug being disconnected from the calling line terminal.

10. In a telephone exchange system, a main switchboard provided with subscribers' multiple line terminals, means for answering 80 calls, an auxiliary switchboard, line seeking switches automatically controlled for trunking calls thereto and means controlled by the auxiliary operator for effecting the completed connection. 85

11. In a telephone exchange system, subscribers' lines, a main switchboard and an auxiliary switchboard, means at said main switchboard for answering calls and for completing connections, and additional line seeking means for transferring calls to said auxiliary switchboard, automatic switches adapted to effect a connection with a called subscriber's line and means at the auxiliary board for controlling said automatic 95 switches.

In testimony whereof I affix my signature in presence of two witnesses.

EDWARD E. CLEMENT.
